CLOCK

Philippe Vannini, Zug, Switzerland, assignor, by
mesne assignments, to Landis & Gyr, A-G.,
of Zug, Switzerland, a limited joint stock com-
pany of Switzerland

Application June 27, 1928, Serial No. 288,692,
and in Switzerland July 19, 1927

5 Claims. (Cl. 58—129)

The invention relates to new and useful improvements in clock mechanisms, and more especially to new and useful improvements in devices for supporting, positioning and locking the clock movement and pendulum as required for running and for shipment.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawing, referred to herein and constituting a part hereof, illustrates one embodiment of the invention, and together with the description, serves to explain the principles of the invention.

Of the drawing:—

Fig. 1 is a front elevation of a device embodying the invention; and

Fig. 2 is a central vertical section taken on line 2—2 of Fig. 1.

The invention is directed primarily to providing novel and useful devices for permitting the spring pendulum of a clock to be optionally and alternatively freely suspended in operating position while running, or to be locked firmly in position for shipment or transportation; and preferably in connection therewith, and forming a part of the same devices, with means for firmly locking the clock movement in suspended position while running, and permitting its free removal for shipment or transportation.

Referring now in detail to the embodiment of the invention illustrated by way of example in the accompanying drawing, a portion of a clock casing 1 is shown and supported thereon and fastened thereto is a pendulum and clock movement supporting plate 2. The means for supporting the pendulum in operating position and for locking it in fixed position for transportation, comprises a pair of side-by-side brackets 3 and 4, projecting outwardly from the back plate 2 of the support, and preferably integral therewith. Extending across between the upper rear portion of the bracket plates 3 and 4 is a cross-piece 5, which is likewise preferably integral with the foregoing described structure.

The pendulum 10 may be of any known or other suitable form, and is suspended in a known manner from a spring 11, by a suitable connec-

tion 12 between the top of the pendulum rod and the bottom of the spring. The upper end of the spring is connected at 13 to a transversely-disposed supporting rod 14, which projects outwardly at either side to form a support for the spring and the pendulum. The rod 14 when the pendulum is in operative position, rests at either end in angled recesses 15 and 16 in the upper face of the side brackets 3 and 4. By reason of the angled or V-shaped form of the bottom of these recesses, the rod 14 is self-positioning.

In the embodied form of means for fixing or locking the pendulum in position to be transported without injury, a transversely-extending bar 21 is fixed to the upper end of the pendulum rod 10. The bar 21 is provided with means which interlock with means formed on the side brackets 3 and 4 when the pendulum is moved upwardly; and as shown, the upper surface of the bar 21 is inclined from either side so as to form a V-shaped cross-section, having inclined sides 22 and 23. The under-side edges of the bracket plates 3 and 4 have correspondingly shaped and sized V-shaped notches 24 and 25 formed therein, into which the ends of the bar 21 fit firmly and snugly when the pendulum rod is at the top limit of its movement.

The embodied form of means for optionally moving the pendulum rod up or down vertically, so as to have the pendulum rest in operative position, suspended from the rod 14, or to have it locked firmly in fixed position by pressing the bar 21 into the recesses 24 and 25, comprise a yoke-like pendulum lifting and lowering member, mounted upon and embracing the side bracket structures 3 and 4. This pendulum-positioning device is vertically slidable along, and is capable of being clamped to the side bracket structure in various positions. As embodied, this pendulum-moving device is conveniently formed as a yoke-like slide, having a top reach 29, located above the cross bar 5 of the supporting bracket, this top reach of the slide terminating in vertically-disposed reaches 30 and 31, extending along the outer sides of the brackets 3 and 4. At their bottom ends the vertical reaches 30 and 31 of the guide yoke terminate in inwardly and horizontally extending pendulum lifting and lowering fingers 32 and 33, respectively, which are in line with and are beneath the cross bar 21, which is fixed to the pendulum.

For the purpose of vertically moving the pendulum-positioning device, a screw rod 38 is

screw-threaded into an aperture in the cross bar 5 of the supporting bracket, the screw rod being provided with a knurled turning head 39. The screw rod 38 passes through an aperture in the horizontal top reach 29 of the guide yoke, and collars 40 and 41 on the upper and lower side of this reach of the guide yoke, permit free rotation of the screw-threaded rod 38, but cause the pendulum-positioning device to rise or descend as the screw rod is turned. In the embodied form of guiding and locking means therefor, there are provided guiding screws 43 and 44 which are screw-threaded into the outer sides of the bracket members 3 and 4. These screws project outwardly through longitudinally-disposed slots 45 formed in the side reaches 30 and 31 of the guide yoke, the heads of the screws being on the outer sides of the parts 30 and 31. Thus, by turning the screw rod 38, the pendulum-positioning device may be raised or lowered, and it may be clamped in any longitudinal position or released therefrom by turning the screws 43 and 44.

When the pendulum is to be clamped in fixed position, screw rod 38 is turned to raise the positioning device, and the fingers 32 as they move upwardly will engage with the bottom side of the bar 21, and will move it into and press it firmly against the V-shaped recesses 24 and 25 in the bottoms of the side bracket, thereby securely clamping the pendulum in fixed position. When the pendulum is to be operated, the screw rod 38 is turned, to permit the pendulum to move downwardly until the supporting rod 14 is supported in the V-shaped notches 15 and 16 in the top surfaces of the brackets, at which time the fingers 32 are free from the cross-bar 21, as shown in Fig. 1.

According to certain features of the invention, means are provided, preferably as a part of the pendulum-positioning and locking mechanism, for removably suspending the clock movement in operative relation with the pendulum and for locking it in position when the pendulum is in operative position. As embodied, hook-like supports 51 and 52 are formed on the front faces of the bracket plates 3 and 4 of the supporting device for the pendulum and clock movement. A cross bar 53 is fixed to and extending transversely across the back frame plate 55 of the clock movement 56, and this bar is of corresponding rectangular or other form so as to fit accurately within the supporting faces of the hooks 51 and 52. When this bar rests within the supports 51 and 52, the clock movement is held accurately in operative position with the pendulum, with the escapement of the clock movement in connection with the pendulum by the usual forked arm 57, or in any other suitable manner. The means for locking the clock movement in running position comprises two projecting fingers 58 and 59 formed on the front edges of the side reaches 30 and 31 of the pendulum-positioning device. When the screw rod 38 is

turned downwardly the lower faces of these fingers fit upon the top face of the supporting cross bar 53 of the clock movement, and clamp it firmly in position in the supporting and positioning members 51 and 52. The clock movement is held thus firmly in position until the screw rod 38 is turned to lift the pendulum from operative position. The positional relation for the release of the clock movement from its support in desired relation to the movement of the pendulum can be effected by the positional relation of the supporting hooks 51 and 52 to the pendulum clamping means.

The invention in its broader aspects is not limited to the specific mechanisms shown and described but departures may be made therefrom within the scope of the accompanying claims without departing from the principles of the invention and without sacrificing its chief advantages.

What I claim is:—

1. A clock including in combination a clock movement, a spring hung pendulum, means for lowering the pendulum to suspend it by its spring and for raising it to clamp it in fixed position, and means associated with said means for locking the clock movement in position when the pendulum is hung from its spring and for releasing the clock movement when the pendulum is held in fixed position. 100

2. A clock including in combination a clock movement, a spring hung pendulum, a bar fixed to the pendulum below the spring, a bracket above the bar and movable fingers to raise the bar and pendulum and to clamp the bar between the fingers and the bracket. 110

3. A clock including in combination a clock movement, a spring hung pendulum, a bar fixed to the pendulum below the spring, a bracket above the bar and fingers normally permitting the pendulum to be supported by the spring but movable to raise the bar and pendulum to clamp the bar between the fingers and bracket. 115

4. A clock including in combination a clock movement, a spring hung pendulum, means for holding said pendulum in fixed position or for releasing the same whereby it is permitted to hang from its spring and means associated with said means for locking said movement in position when the pendulum is hung from its spring. 125

5. A clock including in combination a clock movement, a support therefor, a spring hung pendulum, a bar attached to said pendulum above the spring, a bar attached to the pendulum below the spring, a vertically slid able member on said support adapted to support the lower bar or to move away therefrom to permit said upper bar to support the pendulum from said support whereby the pendulum may be supported either above or below said spring and means on said vertically movable slide to lock the clock mechanism in position when the pendulum is free to swing. 130 135
